UNITED STATES PATENT OFFICE.

CLARENCE H. JACK, OF VERSAILLES, PENNSYLVANIA, ASSIGNOR TO LAYTON FIRE
CLAY COMPANY, OF MCKEESPORT, PENNSYLVANIA.

PAVEMENT.

Application filed March 3, 1927. Serial No. 172,368.

This invention relates to a monolithic one course pavement, and has for its object to provide a permanent wear resisting one course monolithic terra cotta block pavement that will be noiseless, smooth, stand heavy traffic and economical to construct and keep in repair.

Pavements that approach somewhat the characteristics aforesaid are constructed of 10 paving block laid on sand, gravel and broken stone, with sand or asphalt filler. The bottoms of the blocks are flat whereby when the blocks are compressed with only one weight of roller, not over ten ton covering 15 ten feet, the blocks get to working and rocking and allow the water to get in from above which finally reaches the earth underneath and the pavement soon goes to pieces. Thicker foundations were tried, also grout 20 filler, but the thicker foundation did not seem to remedy the fault and the grout filler was a failure, as the expansion of the pavement caused the blocks to either crush or raise from the foundation. The present invention 25 overcomes these difficulties by producing a structure which is homogeneous throughout its depth, and waterproof, under such conditions the water cannot get into it and further any water in the foundation will work its way out through the blocks, these latter provided with openings or channels, thereby resulting in stability 30 and preventing displacement of structure, or any parts thereof under the heaviest traffic.

In the practical construction of brick block pavements the above mentioned defects have been recognized and different modes of laying have been adopted to overcome working, crushing and the entrance of 40 moisture into the roadbed from above which causes disintegration of the foundation of the pavement. The most effective of which is the laying of the pavement on a bed of concrete with a thin layer of cement and sand between the blocks and concrete and squeezing the asphalt into the joints. This combination overcame some of the defects, but makes a hard, rough and noisy pavement, and it was found, that on account of the moisture in the aggregates of the concrete, that this concrete base would dry out and crack and the entrance of moisture would get into the roadbed. To overcome 50 this, the thickness or strength of the con-

crete was increased, to the extent that it made these pavements too expensive for ordinary use, besides being rough and hard. A pavement in accordance with this invention not only combines the advantages of the 60 pavement referred to, but also produces greater stability, a noiseless and a smooth pavement at the lowest cost.

With the foregoing and other objects in view the invention consists of the novel production of a pavement, in a manner as hereinafter described and more specifically referred to, and as illustrated in the accompanying drawings wherein is disclosed an embodiment of a pavement in accordance 70 with this invention, as well as the elements of the pavement and the means for producing certain of such elements.

In the drawings wherein like reference characters denote corresponding parts 75 throughout the several views:

Figure 1 is a perspective view of a paving block in accordance with this invention employed in the production of the pavement.

Figure 2 is a section on line 2—2 Figure 1. 80
Figure 3 is a section on line 3—3 Figure 1.

Figure 4 is a fragmentary view, in perspective, of a pavement constructed in accordance with this invention.

Figure 5 is a transverse sectional view of 85 a pavement constructed in accordance with this invention.

Figure 6 is a top plan view of the mold for producing a pair of connected paving blocks.

Figure 7 is a top plan view of the pair of 90 connected paving blocks which are produced by the mold shown in Figure 6.

Referring to Figures 1, 2 and 3 of the drawings, which illustrates a paving block 95 in accordance with this invention, the body portion of the block is referred to generally by the reference character 1 and preferably is of rectangular contour. The top 2, as well as the sides 3, 4 of the body portion 1 are smooth and uninterrupted throughout. The sides 3, 4, at the lower terminal portions thereof are oppositely bevelled as at 5, 6 respectively. The body portion 1 is formed with a lengthwise extending groove 100 7 which is coextensive with the length of the body portion 1 and said groove opens at the bottom 8 of the block. The upper part of the wall of the groove 7 is of circular contour as indicated at 9 and said part 9 105 110

terminates in a pair of oppositely extending inclined wall-forming parts 10, 11 which terminate in the bottom 8 of the body portion 1. The wall-forming parts 10, 11, in connection 5 with the bevels 5, 6 form the body portion 1 at the lower part thereof with a pair of tapered projections 12 and with the outer sides of said projections of less height than the inner sides thereof and this is caused by 10 the height of the wall-forming parts 10, 11 being greater than the bevels 5, 6. In cross section the groove 7 is substantially similar to a key hole shaped opening. The groove 7 provides what may be termed a pocket formed 15 in a manner to receive the earth for the purpose of anchoring the blocks in position. The block is so designed as to have sufficient depth that by laying it on a specially prepared roadbed that it will require no other 20 foundation. The shape of the block will provide for the forcing of the earth therein and compress it thereby forming a key which will connect the block to the natural earth.

The body portion 1 is formed at each side 25 of the groove 7 with a set of lengthwise extending openings 13 and each of the projections 10 are formed with a lengthwise extending opening 14 of greater diameter than any of the openings 13 and which provides a drain. Below each opening 14 the body portion 1 is formed with an opening 15. The openings 13, 14 and 15 extend from the end 16 of the block to the end 17 thereof. The ends 16 and 17 of the block are smooth. 30 The openings 14, when the blocks are set up, will provide a continuous drain from one side of the pavement to the other and drain the moisture out of the pavement during the rolling and compressing and after construction. The openings 13 and 15 are provided 35 for the entrance of the filler, to be herein-after referred to, into the body portion 1.

Referring to Figure 6 a mold is illustrated, to produce a pair of oppositely extending connected blocks 18, 19 (see Figure 7) and the said blocks are severed at the points indicated 20, thereby providing for a block of the form as shown in Figure 1 of the drawings. The mold includes a body 45 portion 21 provided with a core 23 to form the groove 7 and said body portion 21 is furthermore formed with vertically disposed pegs 24, 25, 26. The pegs 25 are of greater diameter than the pegs 26 and these latter 50 are of greater diameter than the pegs 24. The number of pegs 24 provide for the forming in the block the group of openings 13. The number of pegs 25 will provide for the forming of a pair of openings 14 in each 55 of the blocks and the number of pegs 26 will provide for the forming of the pair of openings 8 in the blocks. The body portion 21 is constructed with four sets of pegs 24, two pair of pegs 25 and four pair of pegs 60 26 and the core 23 is of such shape, that

in connection with the number of pegs as stated, will provide for the simultaneous molding of the pair of connected blocks 18, 19. The core 23 is constructed with a pair of spaced circular end parts 28 and an intermediate part 29 formed with a pair of oppositely disposed V-shaped portions 29' arranged between, merge into and project beyond the circular end parts 28. The body portion is further formed with oppositely disposed V-shaped formers opposing, spaced from the V-shaped portions 29' and providing the bevelled portions 5, 6 of the block. The V-shaped portions 29' form the inclined wall portions 10, 11. 70 75 80

With reference to Figures 4 and 5 the pavement is indicated at 30. The ultimate base of a foundation is the earth, take any road when it is dry and you can drive a heavy load over it with scarcely a wheel mark, therefore the pavement is built with the idea in mind of preserving this condition. The openings in the blocks will drain the water or moisture out of the pavement during construction, and also after the pavement is completed, as these openings will make a continuous drain from one side of the road to the other and will not fill up with the filler to any great extent as the earth or other material will squeeze up a sufficient distance to protect them from the filler. The projection of the blocks, at the bottom thereof are formed in such a manner that when the blocks are squeezed into the roadbed by compression they will force the earth or other material into the grooves and pack it forming a key that will hold the blocks in place and connect them with the earth below. 90 95 100

The roadbed is first compressed and leveled off to the desired grade, all stone or other substances are removed from the surface thereof for a distance of six inches underneath. The roadbed is sprinkled and brought up to conform to the cross section of the pavement required when finished and all soft and spongy material is removed and replaced with suitable materials. The same is brought up to the grade with a template made in the shape of the top surface required when finished and the blocks are laid in even parallel courses transversely to the fine of the pavement, care being taken to break joints with the previous course. After the blocks are laid the pavement is cleaned 110 and rolled with a light roller and places not accessible to the roller are tamped, then the pavement is rolled with a heavy roller and places not accessible to the heavy roller must be tamped with a power tamper or other tamper equal to the weight of the roller. 115 120 125

The compressing of the pavement must continue until the key shaped groove in the blocks are filled and compact and the pavement presents a smooth and even surface 130

conforming to the lines and grades given by the engineer. Over this pavement will be poured asphaltic cement of such consistency that it will seek all the spaces around the blocks and the reinforcing holes in the blocks, or rather the openings 13 in the blocks, then there shall be spread thereover red hot kiln dried sand that will pass a one tenth of an inch screen and the sand broomed in immediately while it is hot so that the sand will sink down into the pitch and mix with it, then the pavement is to be rolled or compressed while hot so that it will form a complete substantial conglomerate. In lieu of employing a filler of asphaltic cement and red hot kiln dried sand, lime grout mixed so that it will seek all openings around the blocks and in the blocks and dried sand that will pass a one eighth of an inch screen is employed. Cement grout or plaster of Paris grout mixed with one to two parts of sand may also be used. The sub-grade is smoothed up with a light coat of sand or gravel.

25 The sub-grade is prepared in such a manner as will require no artificial foundation, and all hard substances are removed to within six inches of the block. The sub-grade after being rolled or compressed and brought to conform to the contour of the finished pavement is to be sprinkled with one gallon of water to the square yard of surface. The filler of pitch or bituminous cement is applied hot and of such consistency and such quantity that when applied it will enter the openings in the blocks and the spaces between the blocks and make a coating over all, over which a coating shall be applied of red hot sand that will pass a one tenth of an inch screen while the pitch is hot and in sufficient quantities to fill the spaces between the blocks and make a coating over all. The sand is to be broomed in while hot so that it will sink down into the pitch and mix with the same. Before the pavement is cool it should be rolled until it forms a solid and compact conglomerate. The openings 13 will provide for reinforcing the pavement, in that the filler will enter such openings and further will drain the pavement during construction and after completion.

It is thought the many advantages of a pavement, constructed in accordance with this invention, can be readily understood, and although the preferred embodiment of the invention is as hereinbefore referred to, it is to be understood that changes in the details of construction of the pavement can be had which will fall within the scope of the invention as claimed.

What I claim is:

1. A paving block comprising a body portion formed with a lengthwise extending groove in its bottom, said groove being of

key-hole shape in cross section, the lower part of the wall of said groove being oppositely flared to provide the lower portion of the blocks with tapered parts, said body portion at each side of said groove formed with lengthwise extending openings.

2. A paving block comprising a body portion formed in its lower face with a groove extending lengthwise thereof, the wall of said groove having a circular upper part and a pair of oppositely flared lower parts forming the lower part of said body portion with a pair of tapered portions.

3. A paving block comprising a body portion formed in its lower face with a groove extending lengthwise thereof, the wall of said groove having a circular upper part and a pair of oppositely flared lower parts forming the lower part of said body portion with a pair of tapered portions, said body portion further formed at each side of said grooves with lengthwise extending openings.

4. A paving block comprising a body portion formed in its lower face with a groove extending lengthwise thereof, the wall of said groove having a circular upper part and a pair of oppositely flared lower parts forming the lower part of said body portion with a pair of tapered portions, said body portion formed at each side of said groove with lengthwise extending openings, one of the openings at each side of said grooves being of greater diameter than the other of the openings on such side.

5. A paving block comprising a body portion formed in its lower face with a groove extending lengthwise thereof, the wall of said groove having a circular upper part and a pair of oppositely flared lower parts forming the lower part of said body portion with a pair of tapered portions, said body portion formed at each side of said groove with lengthwise extending openings, one of the openings at each side of said grooves being of greater diameter than the other of the openings on such side, said body portion having the sides thereof at the lower part oppositely bevelled.

6. A pavement consisting of a sub-grade free of artificial foundation, spaced courses of blocks provided with lengthwise extending openings through the body thereof and further formed with grooves in their bottoms for the entrance of portions of the sub-grade therein and with the walls of the grooves coacting with the said portions of the sub-grade to anchor the blocks thereto, and cementitious material including dry sand providing a coating throughout for the surface of the blocks and further extending into the openings and between the courses and between the blocks of the courses.

In testimony whereof, I affix my signature hereto.

CLARENCE H. JACK.
